UNITED STATES PATENT OFFICE.

JOSEPHINE M. HOLMES, OF SIOUX CITY, IOWA.

SAD-IRON HOLDER.

SPECIFICATION forming part of Letters Patent No. 289,526, dated December 4, 1883.

Application filed November 30, 1881. (Model.)

To all whom it may concern:

Be it known that I, JOSEPHINE M. HOLMES, of Sioux City, county of Woodbury, and State of Iowa, have invented a new and useful Improvement in Sad-Iron Holders, of which the following is a specification, reference being had to the accompanying drawings.

The object of my invention is to furnish a sad-iron holder that will secure, first, perfect protection to the operator's hands from both the hot iron and handle; second, an easy yet large and firm hold of the iron; third, cleanliness and durability; and, fourth, be of ready application and removal; and to this end my invention consists of two pieces of wood so shaped, hinged together, and covered as to form where grasped a perfectly-round and soft holder. I attain these objects by the mechanism illustrated in the accompanying drawings, in which—

Figure 1 represents a side view of the holder with all external attachments; Fig. 2, an end view, showing the hinge, spring, and guard in position, as also the inside shape or form of wood; Fig. 3, a vertical section through the middle or round part, and closed by pressure of hand, illustrating the relative position of hand with holder when in use, likewise the overlapping of guards, shutting off all radiating heat from iron below.

Similar parts are designated by corresponding letters in the different views.

The body A is formed by two symmetrical pieces of wood, joined laterally, rounded on top and sides throughout, but below only the middle third is round, forming notch B, which by ends or projections D D, extending low enough down, and with guards E E attached, forms opening B, sufficiently large to admit operator's fingers, thus forming a perfectly-round holder—middle third. Inside both pieces are grooves F F, about one-fourth inch from top, to receive horizontal part of sad-iron handle, and to admit the perpendicular parts and extend the necessary length beyond. The ends d d below groove are cut down to nearly a level with bottom of groove, and from ends in to about one-fourth inch from notch B, leaving ridge G extending along, above, and down both sides or ends of notch B to guard E, meeting that of the opposite side, when the holder is closed, as in Fig. 3, thus rendering it impossible for any

heat from the iron or handle to reach the operator's hands. When this finger-opening B, with ridge G around it, is made the proper length to fit accurately between upright parts of sad-iron handle, and ends D D allowed to remain with simply a perpendicular groove to receive upright parts of handle, all of which is easily done where there is uniformity of size, as is the case with the Troy Glosser or small polishing-irons used by patent ironers, and for which this holder is especially designed, then the holder becomes as firmly fixed upon the handle as if part of the iron itself. After being duly shaped, the two pieces of wood are placed laterally together, and thus retained by a strip of leather tacked full length on top, and over all outside some thick soft substance—such as heavy woolen cloth or felt—and over this soft chamois or sheep-skin leather, all tacked around the ends and lower edges of wood, the leather only through notch B and to inner edge of ridge G, to protect the operator's fingers. The hinges K K are then screwed on both ends, while but one spring, L, suffices to throw the holder open below for ready application and removal. The spring L is made by twisting a piece of wire upon itself and over a knob, fastening it in connection with the hinge above, and below is bent at right angles and driven into wood on both sides, as shown in Fig. 2. To this a catch may be fixed, extending from one side and fastening on opposite one, thus locking the holder securely when closed upon the sad-iron handle. The guards E E, like the hinges L L, are composed of sheet brass or zinc, covered with leather on upper surface and screwed against lower edges of projections D D, forming leather-lined opening B. Each guard is flush with wood inside, both ends; but middle third, or over opening B, projects half-inch, as seen in Fig. 2, overlapping with opposite when closed, as in Fig. 3, to prevent scorching leather and dropping upon the work, as is the case with all cloth holders, soiling and often ruining the work; also, by these interlocking leaves or guards handles of different sizes may be grasped, and yet all radiated heat from iron below cut off, while by the use of wood, with its non-conducting properties and soft coverings, no heat from handle can reach operator's hands. The closely-lying spring below upper surface of holder

is entirely out of way, and ample room is afforded for both hands, (always used in polishing.) As a whole, among the many advantages gained by this holder are those derived 5 from its extending beyond upright parts of sad-iron handle and grasping not only the round horizontal, but the upright parts of handle as well, thereby affording a more firm and secure hold, with far better control of iron, 10 and making it especially serviceable for use on the small polishing-iron.

I am aware that prior to my invention a variety of sad-iron holders—cloth, metallic, and wooden, with shields or guards and springs— 15 have been made; but I am not aware that a holder has ever been made or used similar in construction and useful to the class of operators known as "patent ironers," using the Troy Glosser or small polishing-irons, and 20 for which this holder is especially designed and adapted, although useful on any iron.

All the patented holders to which my attention has been directed are designed for and

adapted to large-handled smoothing-irons only, being so constructed as to fit between 25 the upright parts of sad-iron handle, and not extend beyond, as mine; hence are of no service whatever with these small polishing-irons.

I therefore claim as new and desire to secure by Letters Patent—

A sad-iron holder the grasping portion of which is composed of wood, with an outer covering of buckskin, leather, or other analogous material, and constructed with an end spring, substantially as described, located on the end 35 of the holder and below its upper surface, for the purpose of holding apart the two pivoted portions, and provided with overlapping protecting-leaves attached longitudinally to the lower edges of each pivoted portion, substan- 40 tially as described.

JOSEPHINE M. HOLMES.
